UNITED STATES PATENT OFFICE.

FREDERICK O. HEUSER, OF CHICAGO, ILLINOIS, ASSIGNOR TO HEUSER MANUFACTURING COMPANY, A COPARTNERSHIP COMPOSED OF FREDERICK O. HEUSER AND HERMAN F. LENK, OF CHICAGO, ILLINOIS.

CUSHION-SPRING SCREEN-DOOR CHECK.

Application filed July 23, 1925. Serial No. 45,470.

My invention relates to an air cushion spring screen door check adapted to be attached to a screen door for preventing the door from slamming, but at the same time 5 permitting the door finally to close without resistance.

One object of my invention is to provide a device readily attachable to screen doors under any condition of door frame construction, a device which can be attached either to a left-hand opening or a right-hand opening door, and a device which has no permanent attachment to the door casing, and which remains attached to the 15 screen door when the latter is removed for storage, and one which though attached to the door will lie flat so as to occupy only a very small space and permit a number of doors to be stacked one against the other.

20 My invention is illustrated in the accompanying drawings, in which—

Figure 1 is a longitudinal section through the cylinder and piston of my pneumatic door check;

25 Figure 2 is a section taken on line 2—2 of Figure 1;

Figure 3 is an elevation illustrating the means for reversing the mechanism from a left-hand hinged to a right-hand hinged 30 door;

Figure 4 illustrates my invention as it appears when attached to a right-hand hinged screen door;

Figure 5 illustrates my invention as it 35 appears when attached to a left-hand hinged screen door;

Figure 6 is a plan view of a partially 40 opened door, to which my check has been attached, the door being in the position at which the check abutment has left its contact with the door frame, and

Figure 7 illustrates my door check as it 45 appears when turned into position parallel with the door, for storage purposes.

The operating portions of my invention 50 comprise a cylinder 8 within which a cup leather piston 9 operates, a spring 10 being provided for propelling the piston on its non-compression stroke. The end of the cylinder is closed by a cylindrical section 12, provided with a duct 13, which may be closed to varying degrees by a washer 14, controlled by a screw 15. The cylinder

wall is provided with an impressed portion 16 for pressing the cup leather away from 55 the cylinder wall just prior to its reaching the end of its stroke. As shown this portion extends inwardly but it may extend outwardly and may be duplicated at several positions around the cylinder. The piston 60 rod 17 extends through a piston head 18, which serves as a guide for the rod, and by means of the stud 19 as a support for the cylinder. The protruding end of the piston 65 rod 17 is pivotally attached at 20 to the link 21, the pivotal attachment being on the axis of the stud 19 when the piston 9 is completely at the end of its compression stroke. The purpose of this arrangement will appear more fully in the discussion of 70 Figure 7.

Referring now more particularly to Figure 3, it will be noted that the end of the link 21 remote from the pivotal attachment 20 is attached by a rivet 23, to a split post 75 24, the arrangement being such that the post may be moved either to the position shown in solid lines in Figure 2 or to a directly opposite position, the dotted lines illustrating the post 24 as though it had been 80 moved half way between the position illustrated in full lines and the position it will assume when fully moved. The purpose of this arrangement is that the same parts may be used either for a left-hand hinged door 85 or a right-hand hinged door. The protruding end of the post 24 has a reduced diameter, and extends into a rolled cylindrical bearing 25 at one end of the supporting member 26. This cylindrical bearing is 90 slotted at its central point, the post 24 being provided with a cotter pin 27 to hold the post in position. The other end of the supporting member 26 is similarly provided with a rolled bearing member 28 for receiving 95 the stud 19, a cotter pin 30 being provided to hold the stud 19 in place within the bearing cylinder 28. In order to reverse the parts both cotter pins 27 and 30 are removed, the post 24 being then turned 100 through 180 degrees about its pivot 23, and the stud 19 being then turned through 180 degrees by rotating the cylinder on the piston, the support then being replaced upon the post 24 and the stud 19, as will be understood from an inspection of Figures 4 and 5,

which illustrate the same device in its two positions just described.

In the construction of the device the spring 10 is of less strength than the spring 5 ordinarily provided for closing the screen door. This latter spring may be of any usually or ordinary type, one form of which is illustrated at 32 in Figures 5 and 6.

In the operation of the device, when the door is opened, the spring 10 forces the piston 9 and rod 17 outwardly, thus causing the end of the link 21 to remain in contact with the door frame unless it happens that the screen door is opened more rapidly than 10 the parts will follow under the force of the spring 10, in which event the pivotal end 20 of the link 21 will leave the door frame as the door is opened. In any event, when the door is opened beyond the position illustrated in Figure 5, the end 20 of the link 21 leaves the door frame and remains out 15 of contact with the door frame until the door is again returned to a position slightly more closed than as illustrated in Figure 5. 20 When the door arrives at this position the pressure of the end 20 of the link 21 against the frame causes the piston rod 17 to force the piston 9 into the cylinder against the slight pressure of the spring 10 and against 25 the air then compressed within the cylinder. The degree to which this air will be compressed and to which the door will thus be checked is determined by the degree of constriction of the duct 13, but in any event, 30 when the speed of the door is finally checked, the air escapes from the cylinder through the duct 13, thus permitting the spring 32, which, as before described, is of superior strength, to completely close the door.

40 In order to relieve the resistance of the air cushion just prior to the closing of the door, the impressed portion 16 is provided for pressing the cup leather away from the cylinder wall, thus permitting the escape of air past the piston. In the normal position, however, the cup leather is not bent out of shape and therefore does not take a permanent set.

Referring now to Figure 7, it will be noted that for the purpose of storing the door, the pivotal portion 20 of the link 21 may be moved to a position on the axial line of the stud 19 (which position is farther within the cylinder than that which the 50 pivotal point 20 assumes in the regular operation of the check), so that the stud 19 may be turned in its bearing 28 to a position in which the cylinder 8 will lie parallel with and adjacent to the upper rail of the 55 screen door. This is of considerable advantage, since it permits the doors to be stored in small space and relieves the householder of the necessity of removing any of the parts of the check for the purposes of 60 storage. It is also a distinct advantage that

the door check requires no attachment to the door frame, first, for the reason that no unsightly holes or attachment means are left on the frame when the screen is removed, and second, because of the ease with which 70 the door may be removed and replaced at the end and beginning of the fly season.

Although I have shown and described my invention with respect to the details illustrated in the accompanying drawing, it is 75 to be understood that many of these details may be varied without departing from the spirit or scope of my invention.

What I claim is:

1. A door check comprising a cylinder, 80 a piston within the cylinder, a spring for forcing the piston in one direction, a pivotal mounting for the cylinder, a piston rod, a link connecting the piston rod with the mounting for the cylinder, one end of said link being adapted to abut the door frame to force the piston into the cylinder upon the closure of the door.

2. A door check comprising a cylinder and its accompanying piston, a support for the cylinder, adapted to be attached to the rail of a spring closed screen door, a link connected between a part of said support and a piston rod for said cylinder, the length of said link being substantially equal to the 85 distance between the point on said support at which the cylinder is mounted and the point at which one end of the link is mounted, the movable end of the link serving as an abutment against the door frame, the 90 link, piston rod and support forming a triangle by means of which the piston rod is held in a definite position for each different degree of opening of the door, and by means of which the cylinder is guided to the proper 95 axial relation with the piston rod under all degrees of opening of the door.

3. A door check for spring closed doors, comprising a member adapted to be attached to the upper rail of the door, a cylinder mounted to swing in a horizontal plane at one end of said member, a link mounted to swing in the horizontal plane at the other end of said member, the length of said link being substantially equal to the distance between the pivotal support for the cylinder and the link, and a piston rod extending into said cylinder and having one end attached to the free end of said link.

4. A door check for spring closed doors, 100 comprising a cylinder having a piston therein, a mounting for said cylinder permitting the same to be swung in a horizontal plane about a pivotal point substantially on a vertical line with the cylinder head, a piston 105 rod extending through the cylinder head and adapted to guide the cylinder, and a link having one end pivotally attached to the end of the piston rod, and having the other end attached to the door at a point located sub- 110

stantially the same distance from the pivotal support for said cylinder as the length of the link.

5. An air cushion door check for either right or left hand hinged doors, comprising a support adapted for attachment to the door rail, a pair of vertically extended members pivoted in the opposite ends of said support, a link attached to one of said members, a cylinder attached to the other of said members, said members being reversible in said support, and one of said members being reversible on said link, whereby the same parts may be utilized for assembling the mechanism in corresponding positions, either on a left-hand hinged or a right-hand hinged door.

6. A door check for screen doors, comprising a supporting member, a link attached to one end thereof, a piston rod attached to the other end of the link, a cylinder pivotally attached to the other end of the supporting member, the length of the link being equal to the distance between the points of attachment of the link and cylinder on said supporting member, the movable end of the link being provided with a pivot which may be moved into axial alignment with the supporting member for the cylinder, whereby the cylinder and the piston rod may be swung about the axis of the two axially aligned pivots, so that the cylinder, the support, the link and the piston rod lie in substantially the same plane along the face of the door rail.

7. A cushioning device for screen doors and the like, comprising a chamber, a piston therein, a piston rod, a link pivotally attached to the external end of the piston rod,

a pivot for the end of said link, all of said parts secured to the door at a point near the hinged edge thereof, the end of said link remote from its pivotal support being adapted to engage the door frame for causing the operation of the piston within the air chamber.

8. A cushioning device for doors, comprising a cylinder, a cup leather piston within the cylinder, means in the wall of the piston and near one end thereof for permitting air to escape past the cup leather piston to relieve the pressure in the cylinder prior to complete closure of the door, said means being located a sufficient distance from the end of the cylinder that the cup leather of the piston will pass said means when the door is entirely closed.

9. A cushioning device for doors, comprising a cylinder, a cup leather piston operating within the cylinder, a boss extending inwardly from the cylinder wall at a point near one end of the cylinder and serving to press the cup leather away from the cylinder wall as the piston passes the boss for permitting the escape of air past the piston through a part of the range of the movement of the piston in the cylinder.

10. A cushioning device for doors comprising a cylinder, a piston operating within the cylinder, an impression in the cylinder wall between the limits of the stroke of the piston providing means for passage of air from one side of the piston to the other as the piston passes said impression.

In witness whereof, I hereunto subscribe my name this 20th day of July, 1925.

FREDERICK O. HEUSER.
